UNITED STATES PATENT OFFICE.

WILLIAM L. SCHELLENBACH, OF CINCINNATI, OHIO, ASSIGNOR TO THE AMERICAN TOOL WORKS COMPANY, OF CINCINNATI, OHIO, A CORPORATION OF WEST VIRGINIA.

SPEED-CHANGING MECHANISM.

SPECIFICATION forming part of Letters Patent No. 761,324, dated May 31, 1904.

Application filed October 30, 1903. Serial No. 179,138. (No model.)

To all whom it may concern:

Be it known that I, WILLIAM L. SCHELLENBACH, a citizen of the United States, residing at Cincinnati, in the county of Hamilton and 5 State of Ohio, have invented certain new and useful Improvements in Speed - Changing Mechanism, of which the following is a specification.

My invention relates to speed - changing mechanism, and I have shown it in connection with an engine-lathe as applied for varying the speed of the lead-screw.

My invention will be readily understood from the following description and claims and 15 from the drawings, in which latter—

Figure 1 is a front elevation of the head end of a lathe with my improved device applied thereto. Fig. 2 is an end elevation of the same. Fig. 3 is a longitudinal section of 20 my improved device, taken on the line $x-x$ of Fig. 4. Fig. 4 is a cross-section of the same, taken on the line $y-y$ of Fig. 3. Fig. 5 is a perspective view of the housing and shifting-arm of the secondary speed-variator. Fig. 6 is a plan view of the shifting-stem and shield 25 for the latter, and Fig. 7 shows the periphery of the index laid out in plane.

In the present exemplification of my invention, A represents the bed or frame, which 30 may be mounted on suitable legs; B, the head-stock; C, the spindle, and D the lead-screw of an engine-lathe, which may be of any suitable construction. A gear E on the spindle transmits motion to a gear F on a shaft G through 35 the medium of transmitting-gears H I, mounted on a tumbler-plate K for transmitting forward or reverse motion to the gear F. A housing L is arranged to slide longitudinally of the shaft G. This housing is pivoted by bearings $l-l'$, journaled, respectively, on the hub m of an arm M and on the hub n of one of a group, nest, or cone of gears N diversely sized, the cone of gears being secured for rotating together. This cone of gears is splined to the 40 shaft G, and in the form shown the hub n extends from the smallest gear of the cone, the other gears of the cone being mounted on said hub, said gears meshing with the mating

gears of a group, nest, or cone of gears O, diversely sized, on a shaft P. The gears of cone O rotate loosely on the shaft P, except when separately clutched to the shaft. The arm M supports a stem m' , which has a peripheral index m^2 at its outer end arranged in columns of resultants side by side, the number of columns corresponding to the number of mating gears in the cones N O. This peripheral index may be in the form of a plate surrounding the periphery of the stem and secured to the stem. The gears N O may be designated 55 the "supplemental" or "secondary" groups, nests, or cones of gears. I have shown four gears in these mating cones, and the peripheral index correspondingly also contains four columns of resultants. All save one of these 60 columns are concealed by the shield m^3 , which has an opening m^4 for exposing one of the columns in the index. The inner end of this shield forms a plug m^5 , adapted to be received by sockets m^6 , shown along the slot m^7 . The 65 shield also has extensions m^8 , adapted to fit the slot to prevent rotation of the shield. The shield is spring-seated by means of a 70 spring m^9 .

A pinion g is secured to the inner end of the 75 stem m' . The pinion meshes with annular teeth g' on a bushing Q, which is journaled on a sleeve g^2 , surrounding the shaft G. The teeth g' mesh with a pinion g^3 , supported on a stud l^2 on the housing L. The pinion g^3 80 meshes with annular teeth p on shaft P. The shaft P is arranged to slide in bearings $l^3 l^4$ of the housing and has a slot p' , in which are seated opposite keys p^2 , spring-pressed by a spring p^3 into the opposite sockets o of the 85 cone of gears O for clutching the respective gears of the cone O to the shaft P. The ends of the keys are shown half-moon shaped, the sockets being correspondingly shaped, so that the side walls of the sockets will depress the 90 keys into the slot of shaft P when the keys span adjacent gears for permitting the changes in speed to be made while the gears are in motion. It will thus be seen that by revolving the stem m' , which carries the index, lateral 95 movement is imparted to the shaft P, causing

any of the gears of the cone O to be clutched to the shaft P through the keys p^2 , causing selective speed to be imparted to the shaft P through any one of the respective mating 5 gears of the cones N and O, thus indicating the proper ratio of the gears on the exposed portion of the index.

Shaft P is splined to receive gear R, which meshes with a transmitter-gear S, mounted on 10 shaft s, journaled in bearings l^1 in the housing. Transmitter-gear S therefore has four different speeds, or a speed for every column of resultants or threads shown in the index. Transmitter-gear S is adapted to mesh with 15 the respective gears of a group, nest, or cone of gears T, diversely-sized, shown as keyed to the lead-screw D within a casing U, secured to the lathe-bed. The gears T may be designated the "main" or "primary" group, nest, 20 or cone of diversely-sized gears.

The housing L is provided at its lower end with the segment of a gear l^1 , which segment meshes with a segment v, secured to shaft V, journaled in bearings a a'. The shaft V carries a crank v', which has a detent-pin v² engaging holes u on the arc u' of casing U, the 25 detent-pin being spring-pressed into engagement with the holes by spring v³. The holes are so arranged about the arc u' as to make 30 the transmitter-gear S properly mesh with the gears of the cone T.

Secured to the housing L is a latch l', which is made to fit into grooves v⁴ in the segment v, which grooves are spaced to correspond in 35 lateral distance with the respective gears of the cone of gears T. In the form shown the segment v is of substantially the width of the cone of gears T for having the segment l' mesh therewith irrespective of the lateral position of the housing L. The latch l' is shaped 40 to fit the said grooves v⁴ in the periphery of the segment v and is so secured to the housing L that when the housing is thrown back sufficiently to disengage transmitter-gear S 45 from the largest gear of the cone of gears T the latch l' is entirely withdrawn from the groove in the segment v. Consequently the lateral movement of the housing L cannot be made without first raising the crank v' to the 50 detent-hole u⁵, which position entirely disengages the latch from the grooves in the segment v and permits lateral movement of the housing. As latch l' can be engaged only at 55 intervals corresponding with the grooves v⁴, the latter also corresponding with the lateral position of the respective gears of the cone T, transmitter-gear S must always be given the correct lateral position before it can be meshed with any of the gears of the cone T.

60 When the latch l' is disengaged from the groove l', the housing is permitted to be slid sidewise through the medium of stem m' and shield m³, which are grasped bodily for manually shifting the housing laterally, the housing carrying with it the mating cones of gears 65

N and O with the means for causing selective operative connection between said cones and the shaft P and the transmitter-gear S, thus carrying with it what may be termed the "speed-variator" for the main cone of gears 70 and constituting a self-contained slidable speed-box. Moving the housing thus laterally places the transmitter-gear S in lateral position for causing it to be selectively meshed with any one of the gears of the main cone of 75 gears T, transmitting a speed to each of said gears dependent on the speed transmitted to the transmitting-gear through the medium of said secondary speed-variator, which in the example shown embraces four different 80 speeds. Each of these four different speeds is adapted to cut a given series of threads, and each of these series is shown in a separate column of resultants on the index. The gear of the main cone employed to cut each thread in 85 a given column is indicated by a number to correspond with each gear in a column adjacent to the column of resultant threads, the gears of the main cone being instances as eleven in number. The resultants in each 90 column may properly be termed "primary" resultants, being the resultants obtained through the primary speed-variator, and the columns themselves may properly be termed "secondary" columns, being the columns of 95 resultants obtained through the secondary speed-variator. The sockets o are numbered to correspond with the numbers in said adjacent column of the index, and as these sockets are spaced to correspond with the gears of 100 the main cone it will readily be seen that transmitter-gear S may be adjusted laterally to engage with any one of the gears of the main cone and have its correct numbered socket shown by the column on the index exposed by the opening in the shield m³, which shield fits into the proper numbered socket o 105 so shown for producing the number of threads indicated in the index.

Instancing the operation it may be assumed 110 that three threads per inch are to be cut. The knurl of stem m' is turned until the column of the index containing three threads is exposed through the opening in the shield m³, thereby simultaneously shifting the keys p² 115 for proper setting of the supplemental speed-variator. Opposite three threads will be found the figure "7." The crank v' is lifted so as to engage detent-pin v² with hole u⁵ and transverse movement given the stem m' 120 and shield m³ to engage shield m³ into socket numbered "7." Engaging the pin v² with proper hole u properly meshes the transmitting-gear S with the proper gear of the main cone T. 125

Having thus fully described my invention, what I claim as new, and desire to secure by Letters Patent, is—

1. In combination, a self-contained slid- 130 able variable-speed box, a group of diversely-

- sized gears, and a transmitter-gear on the speed-box arranged to mesh with the respective gears of said group of gears.
2. In combination, a self-contained slideable variable-speed box, a pair of shafts for the same, a pair of supplemental groups of mating diversely-sized gears for the said shafts, clutch mechanism for causing operative connection between said shafts through selective mating gears of said supplemental groups of gears, and a transmitter-gear, and a main group of diversely-sized gears, said transmitter-gear arranged to mesh with the respective gears of said main group of diversely-sized gears.
3. In a speed-changing mechanism, the combination with a driving-shaft and a driven shaft, of a self-contained slideable speed-variator pivoted about one of said shafts and a group of diversely-sized gears for the other of said shafts arranged to be selectively interconnected, and transmitting mechanism, substantially as described.
4. In a speed-changing mechanism, the combination with a driving and a driven shaft, of a self-contained laterally-movable speed-variator comprising within itself means for varying speed, said self-contained speed-variator pivoted about one of said shafts, a group of diversely-sized gears rotatively secured to the other of said shafts, and means for causing selective connection between said self-contained speed-variator and said group of diversely-sized gears, and means for locking the same in connected position.
5. In speed-changing mechanism, the combination with a driving-shaft, a driven shaft, of a main group of diversely-sized gears imparting motion to the driven shaft, a rockable and sidewardly-slideable housing, opposing groups of diversely-sized mating gears journaled therein, means for selectively transmitting speed through said mating gears, and a transmitter-gear mounted on and movable with said housing and arranged to selectively engage the respective gears of said main group of diversely-sized gears.
6. In combination, with speed-changing mechanism, a shifting-stem having peripheral index arranged in columns of resultants.
7. In combination, with speed-changing mechanism, a shifting-stem having secondary columns of primary resultants.
8. In combination, with variable-speed mechanism, a rotating part having a partially-exposed index, the rotation of which influences the speed of the variable-speed transmission.
9. In combination, in speed-changing mechanism, a group of diversely-sized gears, a self-contained speed-variator arranged to selectively engage said gears, and a single handle for varying the speed of said variator and shifting the same laterally with relation to said group of gears.
10. In combination, a speed-variator and means for varying the speed thereof, said means comprising a stem having a partially-exposed peripheral index for indicating the relative variation caused by the turning of 70 said stem in effecting speed change.
11. In combination, a pair of shafts, a pair of opposite groups of diversely-sized gears mounted thereon, means for selectively clutching the gears of one of said groups to its shaft, 75 said means comprising a rotatable stem having a peripheral index indicating which gear is clutched to said shaft.
12. In speed-changing mechanism, the combination of a shaft, a housing pivoted thereabout, a second shaft on said housing, a group of diversely-sized gears fast to the first-named shaft, a group of diversely-sized gears loose with relation to the second-named shaft, clutching mechanism selectively engaging the gears 85 of said second-named group of gears to said second shaft, and means for moving said clutching mechanism comprising a rotatable stem having a peripheral index.
13. In speed-changing mechanism, the combination of a group of diversely-sized gears, a speed-variator and transmitter-gears therefor, means for varying the speed produced in said speed-variator, said means comprising a stem having a peripheral index, means permitting lateral adjustment of said stem and speed-variator and causing selective connection between said transmitter-gear and the respective gears of said group of gears, a longitudinally-shiftable shield having opening 90 partially exposing said index, and a part having locking-faces engaged by said shield locking said stem and speed-variator in selective lateral position.
14. In speed-changing mechanism, the combination of a driving-shaft, a laterally-slideable arm taking about said shaft, a housing pivoted about the axis of said shaft and movable with said arm, a supplemental speed-variator mounted on and slideable with said housing, a stem for effecting speed change in said supplemental speed-variator mounted on said arm, a main group of diversely-sized gears, and a part having a slot through which said stem projects, said part also having a series of sockets along said slot corresponding to the respective gears of said main group of diversely-sized gears.
15. In speed-changing mechanism, the combination of a driving-shaft, a laterally-slideable arm taking about said shaft, a housing pivoted about the axis of said shaft and movable with said arm, a supplemental speed-variator mounted on and slideable with said housing, a revolute shaft journaled on said arm and connected with said supplemental speed-variator for affecting speed change, said shaft carrying an index, and means for permitting lateral adjustment and locking of said shaft.

16. In speed-changing mechanism, the combination of a housing, a plurality of groups of diversely-sized mating gears on said housing, means comprising clutching mechanism causing transmission through selective mating gears of said groups, means for moving said clutching mechanism comprising a stem having a peripheral index, a main group of diversely-sized gears, and a transmitter-gear in train with the groups of gears on said housing adapted to selectively mesh with the respective gears of said main group of gears.
17. In speed-changing mechanism, the combination of a housing, a shaft about which said housing is pivoted, a group of diversely-sized gears rotatable with said shaft, a second shaft on said housing, a group of diversely-sized gears loose on said shaft and mating said first-named group, a clutch between said shaft and last-named group of gears for selectively causing engagement between the respective gears of said group and the shaft, means for moving said clutching mechanism comprising a stem having a peripheral index, a main group of diversely-sized gears, and a transmitter-gear on said housing in train with the groups of gears on said housing and adapted to selectively mesh the respective gears of said main group of gears.
18. The combination, in speed - changing mechanism, of a group of diversely - sized gears, a laterally - slideable speed - variator, means for causing selective connection be-

tween said speed-variator and the gears of said group of gears and comprising a segment on 35 said speed-variator, a rock-shaft, and a segment on the rock-shaft of substantially the length of said group of gears extending longitudinally of the same and meshing said first-named segment, substantially as described. 40

19. The combination, in speed - changing mechanism, of a group of diversely - sized gears, and a laterally-slidably speed-variator, means for causing selective connection between said speed-variator and group of gears 45 comprising a pair of segments, one of said segments of substantially the length of said group of gears, said pair of segments having locking means between them compelling correct lateral adjustment of said speed-variator 50 with the several gears of said group of gears, substantially as described.

20. In combination, a self-contained laterally-movable speed - variator, variable-speed and transmitter mechanism therefor, and a 55 second speed-variator with which the mechanism of said first-named speed-variator is arranged to variously engage for changing speed.

In witness whereof I have signed my name 60 hereto in the presence of two subscribing witnesses.
